UNITED STATES PATENT OFFICE.

HENRY E. REEVE, OF NEW YORK, N. Y., ASSIGNOR TO AUTOMATIC FIRE ALARM COMPANY, OF NEW YORK, N. Y., A CORPORATION OF NEW YORK.

THERMOSTAT.

No. 845,894.

Specification of Letters Patent.

Patented March 5, 1907.

Application filed February 2, 1906, Serial No. 299,100.

To all whom it may concern:

Be it known that I, HENRY E. REEVE, a citizen of the United States, residing at New York, county of Kings, State of New York, have invented certain new and useful Improvements in Thermostats, of which the following is a full, clear, and exact description.

My invention relates to improvements in thermostats, and particularly an improvement in the type shown in my former patent, No. 657,359.

The object of this invention is to simplify the construction and render it less liable to short circuits or deterioration from any cause, such as corrosion.

The invention consists in improvements the principles of which are illustrated in the accompanying single sheet of drawings.

Briefly, it comprises a casing inclosing the thermostatic device which is insulated from the casing and in which the leading-in wires are so sealed as to prevent corrosion or short circuits.

Figure 1 is a plan view of a thermostatic device embodying the improvements of my invention. Fig. 2 is a sectional view of the same. Fig. 3 is a view of the interior of the device, the bottom of the casing being removed.

1 indicates the main portion of the casing, which is preferably formed of sheet metal. 2 is the bottom of the casing suitably secured to the body, as by spinning over the rim.

While the casing performs an exceedingly important function in the completed device as a whole, the parts which constitute the true thermostatic device are the only ones through which current passes. These are connected together and mounted in the casing, but suitably insulated therefrom.

3 is a cup-shaped metallic member having insulating-disks 4 and 5, preferably of mica, arranged on each side.

6 is a compound bar formed of two metals having different coefficients of expansion. One end of this bar is secured to plate 7.

8 is an adjustable contact-point carried by a plate 9, adjacent the other end of the bar 6.

10 and 11 are plates shaped corresponding to plates 7 and 9 and located above the insulating-disk 4. The plates 7 and 9 are located below the insulating-disk 5. The

parts are held together and electrical connection made between the plates 10 and 7 and 11 and 9, respectively, by rivets or eyelets 12 and 13. The leading-in wires 14 and 15, through which current is adapted to pass, are connected to the plates 10 and 11, preferably by soldering the ends, so that permanent electrical engagement is effected.

16 and 17 are insulating disks, preferably of mica, arranged above and below the plates of the thermostatic device, respectively, for insulating it from the top and bottom of the casing. The upper disk 16 has a passage or recesses for the protrusion of turned-up portions of the plates 10 and 11, and the bottom disk 17 has a recess or perforation centered by the boss 18. The outside and bottom of the casing are so formed and spaced apart that the compound bar 6 does not touch either in its expanded or contracted position. When the temperature device is raised to the predetermined degree, the movable end of the bar 6 engages the contact 8 and completes the electrical circuit.

Heretofore difficulty has been encountered in thermostatic devices caused by corrosion of the parts. This is overcome in my device.

19 is a collar or tubular member, preferably formed integral with the body of the casing and surrounding the junction of the leading-in wires.

20 is a cap or collar, preferably formed separate, but adapted to be fitted onto the collar and be brazed or soldered thereto. This cap and collar form a chamber which has passages in the form herein shown through the sides of the cap for the leading-in wires.

21 and 22 are cup-like extensions arranged around these lateral openings, which are preferably provided and filled with suitable material which is not affected by heat.

25 indicates a body of suitable insulating material, which is preferably introduced into the chamber in a melted condition by pouring it in through an opening in the top of the cap. The opening in the top is closed only by this insulating material when it solidifies. By this means the space between the plates 10 and 11 and the space within the chamber of the collar surrounding the leading-in wires is filled solid with material which prevents the entrance of moisture and prevents short-circuiting. The importance of these features will be appreciated by those skilled in

this art and acquainted with the practical utilities of such a device.

What I claim is—

1. In a thermostatic device, a casing, terminal plates contained therein, means connected thereto for automatically effecting the circuit upon change of temperature, and a chamber adjacent the terminal plates to which the leading-in wires pass, and insulating material filling and closing said chamber.

2. In a thermostatic device, a casing, automatic short-circuiting mechanism contained therein, a chamber having entrance-passages for the leading-in wires, cups surrounding the passages, and insulating material contained within said cups and said chamber.

3. A thermostatic device comprising a casing, automatic short-circuiting mechanism contained therein, a metallic disk centered in said casing, insulating-disks on each side thereof, two terminal plates mounted above one disk, and two plates for the short-circuiting mechanism mounted below the other disk, rivets connecting the respective plates, conducting-wires attached to the terminal plates, and means for sealing the ends of said wires into said casing and preventing the entrance of moisture.

4. In a thermostatic device, a casing, a metallic disk, a pair of terminal plates, a pair of supporting-plates, a compound bar having one end secured to one supporting-plate, an adjusting-contact carried by the other supporting-plate adjacent the opposite end of said bar, means for connecting corresponding terminal and supporting plates, and means for insulating said terminal and supporting plates from said metallic disk and from said casing.

40 5. A thermostatic device comprising a casing, an insulating-disk centered and supported by the bottom of the casing, an automatic circuit-closing mechanism supported above said disk, terminal plates, electrical means of connection between said plates and said circuit-closing device, and insulating

material for sealing in said terminal plates to prevent the entrance of moisture.

6. In a thermostat, a metallic disk, an insulating-disk on each side thereof, four plates, 50 two situated beyond each disk, rivets for securing said plates and disks together and forming a rigid body, means for automatically effecting the current through said plates upon changes of temperature and an imperforate casing surrounding and inclosing said parts.

7. A thermostat comprising a casing having top and bottom portions, a metallic disk, two supporting-plates, rigidly secured to but 60 insulated from said disk, a curved bar carried by one plate and susceptible to changes of temperature, a stationary contact carried by the other plate and disks of insulating material spacing said metallic disks and said plates 65 from the top and bottom portions of the casing, and means for centering the parts in said casing.

8. A thermostat comprising a metallic disk, a pair of terminal plates arranged on 70 one side thereof but insulated therefrom, a pair of supporting-plates, corresponding to said terminal plates, arranged on the other side of said disk but insulated therefrom, means for securing the corresponding terminals and supporting-plates to said disk and 75 electrically connecting them to each other, and parts carried by said supporting-plates adapted to change the conditions in an electric circuit upon change in thermal conditions.

9. A thermostat comprising a rigid disk, a pair of terminal plates arranged on one side thereof, a pair of supporting-plates arranged on the other side, rivets securing said plates to 85 each other and to said disk and a thermal alarm device carried by said supporting-plates.

HENRY E. REEVE.
